REACTANCE TUBE TIMING MODULATOR

Robert W. Clark, Teaneck, N. J., assignor to Radio Corporation of America, a corporation of Delaware

Application May 26, 1943, Serial No. 488,586

2 Claims. (Cl. 179—171.5)

1

The invention concerns new and improved tube reactances and the same in an improved high frequency signalling system of the type wherein a tube reactance effect is developed and used to modulate the timing of oscillatory energy generated in a tuned circuit or set up in a tuned circuit by an external source.

The invention is in particular applicable to circuits and systems operating at high frequencies such as 100 megacycles and above.

An object of this invention is to simplify and improve the operation of timing modulation systems to be used at high frequencies.

In systems of this type known heretofore the phase quadrature relation between the reactance tube output electrode voltage and the reactance tube control electrode voltage is obtained by lumped capacities, inductances and resistances. At the higher frequencies the use of these lumped circuit constants is not particularly feasible because of distributed capacities of inductances and resistances and inductance of leads such as those to capacities and between tube electrodes and circuit elements.

An object of my invention is to provide a new and improved reactance tube circuit wherein the phase shifting network is comprised of reactance of small distributed capacity, and to provide a new and improved modulation system using said improved tube reactance.

In my improved system the phase quadrature component is obtained by means of a section of transmission line which per se serves as the phase shifting network as well as the connection.

In describing my invention in detail, reference will be made to the attached drawings wherein:

Figs. 1 and 2 each show the essential features of two embodiments of my variable tube reactance and the tuned circuit to which it is coupled to produce the reactive effect and the connections for controlling the said reactive effect to modulate the timing of wave energy in the tuned circuit.

In the embodiment illustrated in Fig. 1, tube 10 in conjunction with a section of coaxial line 12 forms a regenerative oscillation generator of the grounded anode type. The anode 14 as stated is at ground radio frequency potential and the grid 16 at a radio frequency potential above ground which radio frequency potential is 180° out of phase with respect to the phase of the anode radio frequency potential. The cathode 18 is maintained at a radio frequency potential above ground and the phases of the potentials on the grid and anode are about opposed. The inductance 20 of appropriate value for the frequency involved serves to maintain the cathode above ground radio frequency potential.

In this form of oscillation generator the inner conductor of the coaxial line 12 has voltage nodes at both ends, its effective length being the equiva-

2

lent of one-half of the length of the wave generated. The anode 23 of reactance tube 24 is connected to one end of the inner conductor of the oscillator tank circuit line 12. This holds the anode at a high frequency voltage of a first phase.

Radio frequency energy is induced in pickup loop 25 and is fed to grid 26 of tube 24 by means of a section of transmission line 27. The length of this line 27 is such that the phase of the radio frequency voltage at grid 26 is substantially in quadrature with respect to the voltage on anode 23 of tube 24. Thus the current drawn by tube 24 is about in phase quadrature with the voltage on anode 23 and tube 24 simulates a reactance across one end of the oscillator tank circuit 12, thereby controlling the frequency of oscillation.

Condenser 7 is a radio frequency coupling condenser which couples the oscillator grid 16 to the member of line 12 operating at high radio frequency potential. This condenser 7 also prevents plate direct current potential from reaching the grid 16. Condenser 9 is a radio frequency coupling and direct current blocking condenser connecting the cathode 16 to a point on the same member of line 12. 11 is the grid bias resistance connecting the grid 16 to the cathode 18. 15 is a radio frequency bypass condenser connecting the anode 14 of tube 10 to ground. 20 is an inductance, appropriate for the frequency used, connecting the cathode 18 to ground to maintain the cathode above ground alternating current potential. 13 is a radio frequency bypass condenser connecting the second grid of the reactance tube 24 to ground. 17 is a radio frequency coupling condenser coupling the grid 26 to the inner conductor of line 27. 19 is a modulation coupling condenser for feeding modulating potentials to the grid of the modulator tube 28 and 21 is a radio frequency choke between the anode 23 of tube 24 and the direct current source.

The line 27 is adjusted to have an effective length equal to $\lambda/4$ where λ is the wavelength of the generated oscillations. This line permits adjustment of the relative phases of the voltages on the anode 23 and grid 26 to an exact 90° relation. The length of the line per se may be more or less than $\lambda/4$ since it is dimensioned by adjustment to compensate for tube transit time which is to be considered at high frequencies and also adjusted to compensate for the length of connecting leads such as between the anode 23 and the line 12 and between the grid 26 and line 27.

Modulation may be applied to any element of tube 24 shown, in this case as being applied to grid 26, through modulator tube 28. The current through tube 24 is a determining characteristic of the frequency of oscillation and the current through this tube is regulated by the modulating signal. In this manner the modulat-

ing signal will govern the frequency of the oscillations generated.

The modulated carrier may be derived from a loop coupled to the inner conductor of line 12 or by coupling to an oscillator tube electrode.

While in Fig. 1 the pickup loop 25 is shown at one end of the oscillator tank circuit 12, I may locate this pickup loop anywhere along the oscillator tank circuit. A corresponding adjustment in the length of line 27 must then be made in order that the voltage on grid 26 will be in phase quadrature with the voltage on anode 23.

In Fig. 2 is shown a modification of the circuit of Fig. 1. In Fig. 2, tube 30 in cooperation with the section of coaxial line 31 forms an oscillator of the grounded anode variety wherein the electrode 32 of tube 30 acts as the anode of the oscillator. In this oscillator the grid 40 is at a high radio frequency potential with respect to ground and is coupled by condenser 36 to the inner member of coaxial line 31 at a point where the generated voltage is 180° out of phase with respect to the voltage on the electrode 32 serving as the oscillator anode. The cathode 33 of tube 30 is at an intermediate radio frequency potential being held above ground by the inductance 34. Condenser 35 is a radio frequency bypass condenser coupling the oscillator anode 32 to the grounded member of line 31. This condenser 35 also serves as a direct current blocking condenser. Condenser 36 is the grid radio frequency coupling condenser coupling the grid 40 to the inner member of line 31 and resistor 37 is the grid resistor connecting grid 40 to ground and thence to the cathode 33.

The reactance tube 38 has its anode 39 connected to grid 40 by means of the radio frequency coupling condenser 41, so that the radio frequency voltage on the anode 39 is the same as that on grid 40 and is of a first phase. Inductance 42 presents a high impedance to the radio frequencies, keeping anode 39 and grid 40 at high radio frequency potential above ground. Anode 43 of tube 39 being electron coupled to the generating electrodes is connected to grid 44 of tube 38 by a section of transmission line 45. The length of this line is such that the voltage on grid 44 is about in phase quadrature with respect to said first phase of the voltage on the anode 39 of tube 38. The current taken by tube 38 will then be about in phase quadrature with the voltage on its anode 39 and on grid 40, so that tube 38 will appear as a reactance between grid 40 and ground. This effectively connects a reactance across the grid end of the oscillator tank circuit formed by line 31 and this effective reactance is a determining component of the frequency of oscillations. The plate current of tube 38 is varied in accordance with a modulating signal applied through tube 46 to grid 44 of tube 38, so the frequency of oscillation will vary in accordance with the modulating signal. The modulated output may be taken from a loop coupled to the inner conductor of line 31.

In this arrangement, as in Fig. 1, the line 45 will be approximately $\lambda/4$, but in arriving at the line's dimensioning the length of leads between the line and tube electrodes, of the lead between the grid 40 and anode 39 and the electron transit time in the oscillator tube is considered. At ultra-high frequencies the plate current is not in phase with the grid voltage because of tube electron transit time. To have the plate current in

quadrature with the plate voltage the grid voltage may be more or less than 90° out of phase with respect to the plate current. Thus at ultra-high frequency line 27, or 45 may be considerably less than $\lambda/4$.

In the system disclosed, I have shown in a conventional manner a triode generator at 10 and two grid tubes at 24, 30 and 38. In practice I may use tubes of any type suitable for the purpose.

I claim:

1. In a tube reactance, a two-conductor transmission line wherein high frequency waves are developed, a tube having an electron receiving electrode coupled by a path of low impedance to said high frequency waves, to one of the conductors of said line, whereby voltage of a first phase is set up on said electron receiving electrode, said tube having an electron flow control electrode and an electron source electrode, a substantially direct coupling between said electron source electrode and the other conductor of said line to put the impedance between the electron receiving electrode and the electron source electrode in shunt to the conductors of said line, a second line of a length substantially equal to $\lambda/4$, where λ is the wavelength of the high frequency waves, a tube coupling between one end of said last named line and said first line to feed voltage to said second line, and a coupling between the other end of said second line and the electron flow control electrode of said tube, to feed to said electron flow control electrode a voltage the phase of which is substantially in quadrature with the phase of said voltage of said first phase, whereby a reactive effect is produced in said tube and reflected into said first line.

2. In a reactance tube timing modulation system, a two-conductor transmission line wherein high frequency waves are developed, a tube having an electron receiving electrode coupled substantially directly to one end of one conductor of said line, whereby voltage of a first phase appears on said electron receiving electrode, said tube having an electron flow control electrode and an electron source electrode, a coupling between said electron source electrode and the other conductor of said line to put the impedance between the electron receiving electrode and the electron source electrode in shunt to the conductors of said line, a transmission line of a length substantially equal to $\lambda/4$, where λ is the wavelength of the high frequency waves, an electronic coupling between one end of said last named line and said first line, a coupling between the other end of said second line and the electron flow control electrode of said tube to feed to said flow control electrode a voltage the phase of which is substantially in phase quadrature with respect to the phase of said voltage of said first phase and connections for controlling the transconductance of said tube in accordance with signals.
